ENGINE SUPERCHARGER

Frederick A. Pudge, Boise, Idaho, assignor to
Nevada Engine Corporation, Winnemucca,
Nev., a corporation of Nevada

Application July 11, 1944, Serial No. 544,443

1 Claim. (Cl. 123—119)

The present invention relates to superchargers or means for forcing air into internal combustion engines.

Heretofore in devices for supplying air to engines it has been customary to use devices such as fans or blowers involving rotary elements and, since such devices must frequently operate at extremely high speeds, difficulties of one sort or another are encountered.

Among the objects of the present invention is to eliminate rapidly rotating parts and thus do away with bearing and out-of-balance troubles.

Another object is a supercharger or air supply means which may be operated at low as well as high speeds to supply air to engines of the fuel injection type.

Still other objects will readily occur to those skilled in the art upon reference to the following description and the accompanying drawings in which

Figure 1 illustrates more or less diagrammatically an engine with opposed pistons and showing an application of the supercharger, parts being shown in section.

Figure 2 shows a part of Figure 1 somewhat enlarged.

Figure 3 is a view in elevation of one of the devices.

In the drawings, Figure 1 shows a sectional view of an opposed piston type of engine, the cylinder 10 having therein a pair of pistons 11, actuating suitable crankshafts 12 through connecting rods 13.

In this figure, the pistons 11 are shown at the end of their outward movement with the combustion space 15 between them. The figure also shows passages 16 leading out of the cylinder into a manifold or manifolds 17. These are the exhaust passages.

The air inlet passages are indicated at 20 and as coming into the cylinder from a plurality of bellows type compressors 25.

These compressors 25 may be identical in form and size or may differ somewhat in size or shape depending upon considerations of space and location. Each, however, consists of an oscillatable plate 26 hinged at one end as at 26B by means of an air-tight hinge of suitable flexible material, such as rubber, fixed to the plate 26 and to the stationary base plate 27. The free end of the plate 26 is connected through connecting rods 28 to a suitable actuating portion of the engine such as the crankshaft 12.

The plate 26 is provided with a large number of openings 26A passing through the plate and car-

ries on its under side a suitable valve or diaphragm 29, fixed at two or more of its edges to plate 26 and also provided with a plurality of openings 29A so arranged as not to register with openings 26A.

The plate 27 is fixed to the engine and is likewise provided with a plurality of openings 27A passing through the plate and opening into a suitable chamber 30, in turn opening into a passage 20, these openings being valved by means of a second diaphragm 31 fixed at its edges to the underside of plate 27 and provided with suitable openings 31A arranged in non-registry with openings 27A.

Surrounding the perforated areas of plates 26 and 27 and fixed to the latter and to hinge 26B is a collapsible and distendable bellows diaphragm 35 reinforced, if desired, with suitable cords or wires 38A, the whole assembly of plates and diaphragms being heat insulated as indicated at 40 by suitable material, and secured to the engine in a suitable fashion as indicated by lugs 41.

In the specific application of the device shown in Figure 1, the inlet passages 20 and exhaust passages 16 are covered by the piston 11 until near the ends of the outward stroke of the pistons and accordingly the drive of the plates 26 should be so arranged as to fully collapse the bellows 35 at or just before these passages are uncovered by the pistons. In other types of engine, of course, a different timing of the bellows operation may be used.

In the use of the present device on an engine, the cleaning of the entering air is an important consideration and it is proposed to accomplish this in any easy practical manner by placing over each bellows or group of bellows a housing member 50. This will be in the form of an enclosing metallic box provided in its outer wall with suitable air inlet openings 51 which lead the air into and through a suitable flat filter 52 carried upon the inner face of the wall. Near one end the housing 50 will be provided with a wall or partitions 50A having slots 53 for the ears 53, connected to the connecting rods 28.

As indicated in Figure 1, a single housing 50B may be used to cover two or more bellows.

In applying the housing 50 to the bellows it is preferred to curve the slotted end wall and arrange it closely adjacent the diaphragm 35 so as to provide a reinforcement of the latter against the considerable pressure that builds up within the bellows. The housing will also serve as a safety member by preventing contact of the person with the rapidly oscillating plate 26 or rods 28.

In making the present device the hinge 26B, diaphragms 29, 31, and 35 will be made of any suitable material, such as one of the heat resisting forms of synthetic rubber.

By the use of the bellows type of compressor it is obvious that there can be no dynamic balance difficulties such as may be encountered in rapidly rotating parts but, of course, oppositely placed bellows should be at least statically balanced.

Now having described the invention and the preferred embodiment thereof, it is to be understood that said invention is to be limited not to the specific details herein set forth, but only by the scope of the claim which follows:

I claim:

In an internal combustion engine, air supply

means consisting of a bellows having a stationary plate fixed to said engine structure, an oscillatable plate hinged thereto, means connecting the latter plate in operative relation to a moving part of said engine, valved air inlet means carried by said oscillatable plate, valved air outlet means carried by said stationary plate, a bellows diaphragm sealed to said plates around the valve areas, heat insulating means between said stationary plate and the engine structure, and a housing for said bellows having a wall arranged closely adjacent the outer surface of said diaphragm, said housing being provided with air inlet means and means for filtering the incoming air.

FREDERICK A. PUDGE.
